(57) **CLAIM**

The ornamental design for an electrical connector, as shown and described.

DESCRIPTION

FIG. 1 is a front elevational view of a first embodiment of an electrical connector, showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a right front perspective view showing the top thereof;

FIG. 8 is a left rear perspective view showing the bottom thereof;

FIG. 9 is a right front perspective view showing the bottom thereof;

FIG. 10 is a left rear perspective view showing the top thereof;

FIG. 11 is a right front perspective view thereof, showing the electrical connector with a shutter removed;

FIG. 12 is a front elevational view thereof, showing the electrical connector with the shutter removed;

FIG. 13 is a front elevational view of a second embodiment of an electrical connector;

FIG. 14 is a rear elevational view thereof;

FIG. 15 is a right side elevational view thereof;

FIG. 16 is a left side elevational view thereof;

FIG. 17 is a top plan view thereof;

FIG. 18 is a bottom plan view thereof;

FIG. 19 is a right front perspective view showing the top thereof;

FIG. 20 is a left rear perspective view showing the bottom thereof;

FIG. 21 is a right front perspective view showing the bottom thereof;

FIG. 22 is a left rear perspective view showing the top thereof;

FIG. 23 is a right front perspective view thereof, showing the electrical connector with a shutter removed;
FIG. 24 is a front elevational view thereof, showing the electrical connector with the shutter removed;
FIG. 25 is a front elevational view of a third embodiment of an electrical connector;
FIG. 26 is a rear elevational view thereof;
FIG. 27 is a right side elevational view thereof;
FIG. 28 is a left side elevational view thereof;
FIG. 29 is a top plan view thereof;
FIG. 30 is a bottom plan view thereof;
FIG. 31 is a right front perspective view showing the top thereof;

FIG. 32 is a left rear perspective view showing the bottom thereof;
FIG. 33 is a right front perspective view showing the bottom thereof;
FIG. 34 is a left rear perspective view showing the top thereof;
FIG. 35 is a right front perspective view thereof, showing the electrical connector with a shutter removed; and,
FIG. 36 is a front elevational view thereof, showing the electrical connector with the shutter removed.
The broken line in the figure drawings is included for the purpose of illustrating unclaimed environment and forms no part of the claimed design.
